Inventor
ARTHUR STELLER
By his Attorney Frank D. Fischer.

UNITED STATES PATENT OFFICE.

ARTHUR STELLER, OF NEWARK, NEW JERSEY, ASSIGNOR TO ALLSOOP BROTHERS, OF NEWARK, NEW JERSEY, A CORPORATION OF NEW JERSEY.

FINGER RING.

Application filed April 18, 1925. Serial No. 24,050.

This invention relates to improvements in finger rings and more particularly to types known as solitaire rings in which a single gem is set.

In the usual construction of rings of this type the most prominent or crown portion is provided with a thin flat polygonal plate having a central opening, originally of relatively small diameter, this opening being enlarged to suit the gem, a portion of which protrudes above the plate, which is usually plain or embellished on its outer surface only.

In the instant invention it is an object to provide a concavo-convex crown plate, held in the ornamenteally raised main portion of the ring, with its convex surface outward, the plate being latticed in conformity with the design of the ring, and provided with a plurality of prongs reaching radially into the central opening, these prongs being reduced in length or bent as may be desired.

A further feature of the invention is in the provision of a substantially conical, open-work basket adapted to enter the opening in the plate and be secured to the in-reaching prongs at a point midway in its length, this basket receiving the gem and acting as a setting therefor.

Another aim is in the provision of a ring setting, including a plate and basket, that may be interchanged for another of similar type, but of different dimensions, to accommodate larger or smaller stones without affecting the main body of the ring, the change being readily effected.

These and other analogous objects are accomplished by the novel construction and combination of parts hereinafter described and shown in the accompanying drawing, forming a material part of this disclosure, and in which:—

Figure 1 is a top plan view of a conventional type of ring showing a gem setting made in accordance with the invention.

Figure 2 is a longitudinal sectional view taken on line 2—2 of Figure 1.

Figure 3 is a transverse sectional view taken substantially on the center of the crown portion of a ring and showing a gem set therein.

Figure 4 is a plan view of an ornamenteally perforated holder plate used in the construction.

Figure 5 is an edge view of the same.

Figure 6 is a perspective view of the gem holding basket not notched used in connection with the plate.

Figure 7 is a plan view of a ring, similar to Figure 1, but with the setting elements omitted.

The ring illustrating the application of the invention, is generally designated by the numeral 10, and the type selected is of raised open-work or latticed construction, composed of sides 11 and band or hoop 12, the latter being curved outwardly to produce a raised crown 13 containing a polygonal opening 14, this type of solitaire finger ring being of common construction.

In place of the usual flat crown plate it is preferred to use an ornamenteally perforated polygonal plate 15 its design being in harmony with that of the ring and its polygonal sides adapted to cover the opening 14, eventually being secured by brazing over the wall surrounding the opening, as seen in Figures 2 and 3.

It will also be noted that the perforated plate is curved, its convex surface being outermost, improving the artistic effect, giving a greater depth at the crown, and materially strengthening the construction.

In the plate 15 is a central opening 16 into which project a plurality of prongs 17 which may be trimmed to any desired length, as will hereafter be explained, or bent as may be preferred, the length of these prongs exceeding the intermediate elements 18, formed in the plate design.

A gem holder or basket 19 is formed to present a plurality of fingers 20 extending uniformly upward and inclined outwardly in conical formation from a hollow center 21, the opening in which may be of any desired shape.

It is to be understood that the number of fingers 20 agree with the number of prongs 17 and it will be seen that the fingers are ultimately secured to the prongs at such height as may be required to best exhibit the gem 22, the same being held by the customary notches 23 in the inner sides of the fingers (see Fig. 3).

It will now be apparent that a small gem will require a correspondingly small basket, which may be fitted to the prongs 17 of the crown plate 15 when at their full length while another gem, taking a larger basket, may require the prongs 17 to be

clipped or bent to increase the operative area of the opening 16.

Obviously the basket may be inserted in the prongs to different distances from the crown, (see Figs. 2 and 3) thus raising or lowering the gem, by changing the length of the prongs to suit, such changes being readily accomplished by jewelers without affecting the ring as a unit.

10 From the foregoing it will be seen that a simple device for this purpose has been disclosed in the preferred form of its embodiment, but it is not desired to restrict the details to the exact construction shown, 15 it being obvious that changes, not involving the exercise of invention, may be made without conflicting with the scope of the appended claims.

Having thus described my invention, what I claim as new and desire to secure by Letters Patent, is:—

1. A solitaire finger ring comprising a band having a raised hollow crown, a plate fixed on said crown, said plate having an

opening, a plurality of prongs integral with 25 said plate extending into the opening, and a gem receiving basket secured at the inner ends of said prongs.

2. A solitaire finger ring comprising a band having a raised hollow crown, a convexly curved plate set on said crown, said plate having a central opening, a plurality of prongs extending into the opening from the margin thereof, and an open-work, cup shaped gem receiver fixed in the mentioned 30 35 opening in engagement with the ends of said prongs.

3. A solitaire finger ring comprising a band having a raised hollow crown, a perforate plate fixed on said crown, said plate 40 provided with an opening, and a gem holding basket provided with prongs carried by said plate and secured in the opening in said plate.

This specification signed this 17th day of April, 1925.

ARTHUR STELLER.
